UNITED STATES PATENT OFFICE.

ELLIOT MCKENZIE, OF MOUNTAIN IRON, MINNESOTA.

AUTOMATIC OIL-CAN HOLDER.

Application filed June 10, 1922. Serial No. 567,374.

To all whom it may concern:

Be it known that I, ELLIOT MCKENZIE, a citizen of the United States, residing at Mountain Iron, in the county of St. Louis and State of Minnesota, have invented certain new and useful Improvements in Automatic Oil-Can Holders, of which the following is a specification, reference being had therein to the accompanying drawings.

This invention relates to an oil-can holder, and the object of the invention is the construction of a simple and efficient oil-can holder which will be easy to operate, for placing the can in position upon the holder, and which will also be easy to manipulate for removing the can off the holder.

With this and other objects in view, my invention comprises certain novel combinations, constructions and arrangements of parts as will be hereinafter described, illustrated in the accompanying drawings, and more particularly pointed out in the appended claim.

In the drawings:

Figure 1 is a view in front elevation of a device constructed in accordance with the present invention.

Figure 2 is a side view of my oil-can holder, showing the oil-can in position thereon.

Figure 3 is a side view of the oil-can holder, with the oil-can removed.

Figure 4 is a bottom plan view of the oil-can holder.

Figure 5 is a top plan view of my device. Referring to the drawings by numera's, 1 designates a suitable support, to which is secured my oil-can holder. Said holder comprises a stand 2, which stand includes a base portion 3 and a bracket portion 4; the base portion and bracket portion are integral, but are positioned at right angles to each other. The bracket portion is secured to the support 1, preferably by a screw (dotted lines) 5.

The base portion 3 is slotted at 6, producing an upstanding, integral extension 7, which extension 7 can be fastened by an ordinary screw (not shown) to the support 1, if the operator desires. A depending spring-guide 8 is cut out of the base portion 3, intermediate its edges, for the purpose hereinafter described.

An angular spring 9 is fastened, at 10, to the bracket portion 4, and the upper end of spring 9 extends through the slot 6 and this

spring is provided with an oil-can seat 11 that is adapted to partly receive the oil-can 12 when the oil-can is resting upon the base portion 3, as shown in Fig. 2. This spring 9 serves to push the can off the base portion 3 when the pivotally-mounted fingers 13 are spread sufficiently apart to allow the oil-can 12 to pass therebetween. Each finger 13 is pivotally-mounted on rivet 14, and its outer end is provided with an upstanding portion 15. The upstanding portion 15 is provided with a grip 16, that allows the operator to easily engage the finger, without injuring his hand, to press the finger 13 outwardly to either allow the oil-can to be inserted upon the device, Fig. 2, or allow the oil-can to be removed from the device.

The depending spring-guide 8 has the pivoted fingers 13 normally pressing against its ends, whereas, when the outer ends of the fingers are pressed outwardly by the operator pressing outwardly on the grip 16, coil spring 17 will bear against the guide 8 and keep fingers from being spread unnecessarily wide apart, hence, the guide 8 performs two functions, to wit, it limits too much closing of the fingers together, and it prevents too much spreading of the fingers apart, by reason of the coil spring 17 bearing against the same. It shou'd be noted that the tongue 8 tapers upwardly and therefore the converging side edges form cam edges which will cause the fingers 13 to be moved upwardly into firm gripping engagement with an oil can when they are moved towards each other. The ends of the coil spring 17 are connected to integral, depending, apertured lugs 18 formed upon the fingers 13.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claim.

What I claim is:

In an oil-can holder of the character described, the combination of a base having a support engaging attaching bracket portion formed thereon and depending therebelow, movable retaining means carried so as to operate on the forward portion of said base, a tongue struck from the rear portion of

2
said base and extending upwardly from the rear end of the base, thereby forming a slot which extends from the rear portion of the base toward the center thereof, a leaf spring fixed upon said depending bracket and extending upwardly through said slot and having its upper end formed into a can engaging jaw, the portions of said base surrounding said slot limiting the movement of

said spring forwardly and rearwardly of the base and preventing transverse movement, and said spring cooperating with said movable retaining means, as and for the purposes set forth.

In testimony whereof I hereunto affix my signature.

ELLIOT McKENZIE.
